UNITED STATES PATENT OFFICE.

JOHN B. VAN HOUTEN, OF NEWARK, NEW JERSEY.

DESIGN FOR AN EAR-RING AND PENDANT.

SPECIFICATION forming part of Design No. 14,518, dated December 25, 1883.

Application filed July 23, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Rings and Pendants; and I do hereby declare the following to be a full, clear, and exact description of the same, such as will enable others skilled in the art to which it appertains to make and use the same, reference being had to the accompanying drawings, and to letters of reference marked thereon, which form a part of this specification.

15 Of said drawings, Figure 1 is a front elevation, and Fig. 2 a side elevation, of my design, which figures are deemed sufficient to illustrate the same.

The leading feature of this design consists 20 in the peculiar conformation of the pendant portion of the ear-ring, as will be hereinafter described. Said pendant portion is annular or band shaped at A and concaved at b, the

concavities beginning at the edges of the band-shaped portions, substantially as shown 25 in Fig. 2. Above the band-shaped portion the pendant is bifurcated, the forks c extending on each side of the band-shaped portion to about the center of the concaved portion, whereat they project laterally, as at d, and 30 are rounded or knob-shaped.

What I claim is—

The design for an ear-ring or pendant, consisting of an ear-ring or pendant having the bifurcation, between the forks of which the 35 pendant is band-shaped, said band-shaped portion being laterally concaved at b, substantially as shown and described.

In testimony that I claim the foregoing I have hereunto set my hand this 19th day of 40 June, 1883.

JOHN B. VAN HOUTEN.
